N. ROSENFIELD,
PLUMBER'S BENCH,
APPLICATION FILED OCT. 7, 1915.

1,176,489.

Patented Mar. 21, 1916.

UNITED STATES PATENT OFFICE.

NATHAN ROSENFIELD, OF NEW YORK, N. Y.

PLUMBER'S BENCH.

1,176,489.

Specification of Letters Patent. Patented Mar. 21, 1916.

Application filed October 7, 1915. Serial No. 54,660.

To all whom it may concern:

Be it known that I, NATHAN ROSENFIELD, a subject of the King of Roumania, and a resident of the city of New York, borough 5 of Brooklyn, in the county of Kings and State of New York, have invented a new and Improved Plumber's Bench, of which the following is a full, clear, and exact description.

10 Among the principal objects which the present invention has in view are: to provide a bench of the character mentioned which may be folded to a diminished compass for storage or transportation; to provide 15 a bench adapted for attachment to the framework of a building under construction; to provide means for bending pipes to obtain different curves thereof; to provide a tool-box having means for storing one or 20 more tools of greater length than the capacity of the box would normally afford; to provide means for steadyng the bench, in service, and to provide means whereby various machines may be attached to said 25 bench.

Drawings.—Figure 1 is a side view of a bench constructed and arranged in accordance with the present invention, the dotted lines therein showing the folded or collapsed condition of the movable parts of the same; Fig. 2 shows a front view of the bench, the dotted lines therein showing pipe bent to different curves thereon; Fig. 3 is a detail view showing a modified form of an anchorage and jack hooks operatively engaging the same; and Fig. 4 is a detail view in perspective of the modified form of the anchor plate shown in Fig. 3.

Description.—As seen in the drawings, a 40 bench when constructed and arranged in accordance with the present invention has a relatively small table 9 which is supported by stiff legs 10 with which it is rigidly connected, and by swinging legs 11 with which it is pivotally connected by means of bolts 12. The active or service position of the legs 11 is regulated and controlled by the hinge jointed brace bars 13. The brace bars 13 are pivotally attached by means of 45 rivets 14 and 15, to the legs 10 and 11 respectively. A stop bracket 16, rigidly attached to one section of each of the bars 13, is so arranged as to engage and hold the opposite section of the bar 13 after the two 50 sections have swung past the center alinement thereof. The table 9 may be used to

secure any machine used in the trade to which the invention pertains. The legs 11 are also held in service position by the cross brace 17, which is pivotally mounted 60 on the back brace 18, and is saw-cut or slotted near the forward end to fit over and engage a cross brace 19 extending between the legs 11. The brace 17 serves the added purpose of supporting the hand wheel 20, 65 which, as shown, is pivotally mounted in suitable bearings and is threaded to engage the threads of a screw bolt 21. The bolt 21 is perforated at the lower end to receive a pin 22. The pin 22 forms a shackle 70 for the jack hooks 23, the engaging ends whereof swing toward each other.

Operation.—When in operation, the legs 10 and 11 are spread and held by the braces 13 and 17, the hooks 23 swung toward each 75 other to engage the flanges of an I-beam 24, or a bracket plate 25, as the case may be. In the ordinary course of employment of the present bench, some means of attachment for the hooks 23 is provided. One 80 form of the means which is provided, is that shown in Fig. 4 of the drawings, wherein the bracket plate 25 has a rectangular eyelet 26 in one wing and a round perforation 27 in the opposite wing. It is through the 85 rectangular eyelet 26 that the two ends of the hooks 23 extend. The perforation 27 is intended for engagement by the head 28 of an expansion bolt 29 of any suitable and conventional shape. 90

From the foregoing it will be seen that a bench constructed as described and as shown in the accompanying drawings, may be erected for use in a building which is in course of construction and wherein the 95 floors have not been laid or wherein the floor beams, such as the I-beams 24 shown in the drawings, are exposed. In such condition, temporary boards 30 are laid crosswise on the I-beams 24, and the hooks 23 100 are dropped to engage the top flanges of said I-beams. The engagement of the hooks 23 with the flanges of the I-beams 24 being established, the hand wheel 20 is manipulated to lift the screw bolt 21 until the 105 force exerted upon the hooks 23 is sufficient to steady the bench in its service position.

To assist in steadyng the bench, the same is provided with a jack 31. The jack 31 has a hexagonal body and is centrally bored and 110 adapted to engage the flanges of a screw 32 which is rigidly mounted upon and extend-

ed from a plate 33. Slidably mounted on the screw 32, at the upper end thereof, is a saddle 34, shaped to encompass the lower edge of a structural floor beam, such as indicated by the numeral 35 in Figs. 1 and 2 of the drawings. Located in the center of the saddle 34, is a spur 36, the office whereof is to sink into the beam 35 to prevent the saddle 34 and parts connected therewith from springing out of engagement with the beam 35. To assist in removing the jack 31, a handle 37 is pivotally connected, by means of a pin 38, to lugs 39 integrally formed on the said jack 31.

15 The swinging legs 11 are provided with cleats 40. The cleats 40, as shown best in Fig. 1 of the drawings, are recessed at 41, to form waists. The recesses 41 are shaped to hold pipe, such as indicated by the dotted lines in Fig. 2, and bearing designating numerals 42 and 43. By placing the pipe as shown by the dotted lines in Fig. 2, under one of the cleats 40 and over the companion cleat on the opposite leg 11, the pipe may be 20 manually bent to any desired curve. If a relatively sharp curve is needed, the pipe is bent as shown by the numeral 43, one section of said pipe being placed in the recess 41 under the cleat 40 on one leg 11 and 25 within the recess 41 and over the cleat 40 on the opposite leg 11. The position assumed by the pipe facilitates the bending to a sharper or shorter radius than is convenient when using the companion or upper cleats 40.

In a convenient position and rigidly mounted on the legs 10, is a tool box 44. The tool box 44 has a cover 45, and in one side thereof a recess or opening 46. The recess 40 or opening 46 is provided to permit the elongated handle of any tool too long for insertion within the tool box.

At the under side of the tool box 44 is rigidly secured a spring latch 47. The latch 47 has a head 48, the office whereof is to engage the end of the cross brace 17 when the said brace is lifted to the position shown by dotted lines in Fig. 1 of the drawings.

50 Claims:

1. A bench as characterized, comprising a table having outwardly-spread rigid legs supporting the rear edge thereof; a plurality of swinging legs pivotally mounted at 55 the forward edge thereof for supporting the same in service; a cross brace extending in service between said rigid legs and said swinging legs for maintaining the service relation thereof, said cross brace being pivotally mounted on said rigid legs and having detachable engagement with the swinging legs; and means mounted on said cross

brace for engaging and drawing upon a standing structure for holding the bench and legs thereof in firm contact with said standing structure. 65

2. A bench as characterized, comprising a table having outwardly-spread rigid legs supporting the rear edge thereof; a plurality of swinging legs pivotally mounted at 70 the forward edge thereof for supporting the same in service; a cross brace extending in service between said rigid legs and said swinging legs for maintaining the service relation thereof, said cross brace being pivotally mounted on said rigid legs and having detachable engagement with the swinging legs; and means mounted on said cross brace for engaging and drawing upon a standing structure for holding the bench and legs thereof in firm contact with said standing structure, said means embodying a feed screw, jack hooks pivotally connected therewith and pendent therefrom, and a screw nut thread-engaged with said screw 75 for lifting the same on said cross brace. 80

3. A bench as characterized, comprising a table having outwardly-spread rigid legs supporting the rear edge thereof; a plurality of swinging legs pivotally mounted at 90 the forward edge thereof for supporting the same in service; a cross brace extending in service between said rigid legs and said swinging legs for maintaining the service relation thereof, said cross brace being pivotally mounted on said rigid legs and having detachable engagement with the swinging legs; and means mounted on said cross brace for engaging and drawing upon a standing structure for holding the bench and legs thereof in firm contact with said standing structure, said means embodying a feed screw, jack hooks pivotally connected therewith and pendent therefrom, and a hand wheel having a threaded hub engaging said screw, said wheel being adapted for manipulation to elevate and depress said screw and hooks connected therewith. 95

4. A plumber's folding bench, comprising a table having a pair of fixed legs and a pair of swinging legs, a cross bar carrying a detachable anchoring device, said cross bar being pivoted at one end to the fixed legs and having a detachable engagement with the swinging legs, whereby the said cross bar with the anchoring device can be folded upward to permit the anchoring device to lie intermediate of the ends of the bench when said bench is folded, and means for holding said cross bar in the folded position. 110
